PROCESS FOR THE LIQUEFACTION AND DE-
COMPOSITION OF AIRFranz Pollitzer, Paris, France, assignor to Gesell-
schaft für Linde's Eismaschinen A. G., Munich,

8 Claims. (Cl. 62—175.5)

In the process for the liquefaction and decomposition or rectification of air, difficulties are encountered due to the presence of small amounts of acetylene in the air.

It has been proposed to avoid the danger of explosions due to the presence of acetylene in the air which is to be subjected to liquefaction and rectification by providing a long air intake pipe which extends beyond the surroundings of the liquefying and rectifying apparatus in order to insure a supply of pure air. It has also been proposed to withdraw from the process liquid oxygen in which the acetylene has become concentrated and to dispose of this oxygen separately and with special precautions so as to avoid the danger from explosions. These expedients, however, are not always successful in avoiding explosions. In the operation of the air liquefying and rectifying process for the recovery of crypton and xenon, which handles large amounts of air, it has been observed that even with concentrations of acetylene which are much smaller than those encountered when the above expedients are employed (e. g. 10—100 parts per million of acetylene in the liquid oxygen calculated in parts by volume of the components in the gaseous state) which concentrations generally have been regarded as being harmless, explosions frequently occur. It has been found to be impossible completely to avoid the presence of acetylene in the air by the exercise of care in the location of the air intake and it has been found to be impossible to vaporize the liquid oxygen containing acetylene without danger of explosion.

In accordance with the present invention difficulties due to the presence of acetylene are avoided by subjecting the air to a special treatment preferably after leaving the compressor and before entering the decomposing apparatus. The treatment may be described generally as one capable of breaking down ozone although it is not asserted that ozone is the cause of the explosions. It may be that other unstable oxygen compounds are present or that particles or entities of higher energy level are present or formed as a result of the physical operations to which the air is subjected. It is practically impossible to prove these possibilities due to the fact that the substances in question are unstable and/or present in such great dilution, e. g. less than one part per 100,000,000, that they escape detection by analytical methods at present available. The treatment of the air by a method designed to break

up ozone is therefore merely a rule of operation because it is not known whether ozone is present or whether it is broken up. It is only known that treatments adapted to break up ozone if it is present are effective.

For example the air, after being compressed, may be additionally heated above the temperature produced by the compression or it may be passed, preferably at the temperature produced by the compression, over catalytic surfaces. One suitable treatment is to pass the air after compression and without cooling through a bed of bog iron ore such as is used for removing sulfur from coal distillation gases. The air may be subjected to a chemical treatment with a reducing agent adapted to destroy ozone. This may be done by injecting the reducing agent in finely divided state into the air or by passing the air through a scrubbing tower where it is contacted with a liquid having a reducing action. In the latter case the scrubbing of the air may serve also to cool the air i. e. to remove the heat generated by the compression.

I claim:

1. In a process involving the compression, cooling, liquefaction and rectification of air, the step which consists in subjecting the air, prior to liquefaction thereof to a treatment for the destruction of ozone.

2. Process as defined in claim 1 in which the air is treated for the destruction of its ozone content following the compression thereof.

3. Process as defined in claim 1 in which the treatment of the air consists in heating it to a temperature above that attained in the compressing operation.

4. Process as defined in claim 1 in which the treatment of the air consists in contacting it with a solid catalyst.

5. Process as defined in claim 1 in which the air after compression and prior to cooling is passed in contact with bog iron ore.

6. Process as defined in claim 1 in which the air is contacted with a reducing agent.

7. Process as defined in claim 1 in which the air is contacted with a scrubbing liquid containing a reducing agent.

8. Process as defined in claim 1 in which the air after compression and prior to cooling is contacted with a scrubbing liquid containing a reducing agent whereby the air is cooled and simultaneously freed of ozone.

FRANZ POLLITZER.
